INVENTOR.

BY *H. J. Miller*

Victor J. Evans

ATTORNEY.

UNITED STATES PATENT OFFICE.

HENRY J. MILLER, OF RIDGLEY, TENNESSEE, ASSIGNOR TO H. J. MILLER & CO., OF RIDGLEY, TENNESSEE, A FIRM COMPOSED OF HENRY J. MILLER, MRS. DELLA MILLER, AND W. H. HICKMAN.

FIRE-STARTER.

1,333,557.

Specification of Letters Patent.

Patented Mar. 9, 1920.

Application filed July 22, 1919. Serial No. 312,472.

To all whom it may concern:

Be it known that I, HENRY J. MILLER, a citizen of the United States, residing at Ridgley, in the county of Lake and State 5 of Tennessee, have invented new and useful Improvements in Fire-Starters, of which the following is a specification.

This invention relates to the class of stoves and furnaces, and has for its object the provision of a device whereby a fire may be quickly and easily started, the device being in the nature of a cage structure within which is disposed a member carrying absorbent fireproof material adapted to be saturated with an inflammable liquid which, when ignited, will start combustion of the fuel within the stove or furnace within which the device is placed.

An important object is the provision of 20 a device of this character provided with a detachable handle whereby it may be readily positioned at the desired location within the stove or furnace and the handle subsequently withdrawn so that the stove doors 25 may be closed.

Another important object is the provision of 30 a device of this character in which the wick supporting axle can be removed without necessitating the removal of the wick, the advantage being that the device will be easy to assemble.

An additional object is the provision of 35 a device of this character which will be very simple and inexpensive in manufacture, highly efficient in use, durable in service, and a general improvement in the art.

With the above and other objects and advantages in view, the invention consists in the details of construction to be herein- 40 after more fully described and claimed, and illustrated in the accompanying drawing in which—

Figure 1 is a side elevation of the device,

Fig. 2 is a top plan view,

Fig. 3 is an end view, and

Fig. 4 is a cross sectional view,

Fig. 5 is a fragmentary view, showing one end in section, and

Fig. 6 is a detail perspective view of one 50 of the axle washers.

Referring more particularly to the draw-

ings, I have shown my device as comprising a rectangular cage 10 which is formed preferably as a single casing and which has its ends formed of intersecting diagonal bars 11 and its sides and top formed as spaced parallel bars 12. The bottom of this cage structure is open. At the points of intersection of the end bars 11 are provided slots 13 which open toward the open bottom of 60 the cage.

Disposed within the slots 13 is an axle 14 which has one end provided with a squared portion 15 engageable by a socket portion 16 formed on one end of a handle 17. The axle 65 14 carries a metallic cylindrical member 18 about which is wrapped asbestos or the like 19 formed in strands and adapted to be saturated with gasoline, coal oil, or other inflammable liquid.

In order that the axle and wick member supported thereon may be disposed bodily within or removed from the cage without removing the wick, I provide upon the axle washers 20 which are disposed against the 70 outer faces of the end walls of the cage and each washer carries a hook 21 which is engageable over the edge of the end of the cage so that the axle and wick cannot become accidentally displaced.

In the use of the device it will be seen that the asbestos or other absorbent material employed, is saturated with the inflammable liquid and the device is placed within a stove or furnace in proper position with 85 respect to the fuel therein and the handle 20 is removed. The inflammable liquid is then ignited with a match or the like and the stove or furnace doors closed, whereupon in a short time the fuel will be ignited and the 90 fire started.

Owing to the particular mounting of the axle, it will be seen that the axle and the wick may be inserted within or removed bodily from the cage without the necessity 95 for the removal of the wick, this feature being advantageous in the initial assembly or in repairing the device.

While I have shown and described the preferred embodiment of my invention it is 100 of course to be understood that I reserve the right to make such changes in the form,

construction, and arrangement of parts as will not depart from the spirit of the invention or the scope of the subjoined claims.

Having thus described my invention, I
5 claim:—

1. A device of the character described comprising a rectangular cage open at one side, an axle extending longitudinally through said cage, a crank handle detachably connected with one end of said axle, a member mounted on said axle within said cage, and non-inflammable absorbent material wrapped about said member and adapted for saturation by an inflammable liquid.

2. A device of the character described comprising a cage member open at its bottom and including end members and spaced parallel side bars connecting the same, an axle extending through said cage longitudinally thereof and detachably associated with

said end members by lateral movement with respect thereto, and an absorbent member on said axle adapted for saturation by an inflammable liquid.

3. A device of the character described comprising a rectangular cage open at its bottom and having ends provided with slots opening toward said open bottom, an axle extending longitudinally through said cage and seating within said slots, a handle on one end of said axle, a metallic cylindrical member secured upon said axle within said cage, a wrapping of absorbent material upon said cylindrical member, washers disposed upon said axle against the outer faces of said ends, and hooks carried by said washers and engageable over the upper edges of said ends whereby to hold said axle in place.

In testimony whereof I affix my signature.

HENRY J. MILLER.
